UNITED STATES PATENT OFFICE.

WILLIAM D. FLEMING, OF EAST DOWNTON, PENNSYLVANIA.

AIR-HEATER.

1,213,178.

Specification of Letters Patent.

Patented Jan. 23, 1917.

Application filed July 21, 1914. Serial No. 852,237.

To all whom it may concern:

Be it known that I, WILLIAM D. FLEMING, a citizen of the United States, residing at East Downingtown, in the county of Chester 5 and State of Pennsylvania, have invented new and useful Improvements in Air-Heaters, of which the following is a specification.

The invention relates to an air heater for use in connection with stoves and in the use 10 of which the air delivered from the points above and beyond the stove and the fuel bed is heated to a considerable degree prior to reaching the ignition point.

The main object of the present invention 15 is the use of the air heater hereinafter termed a preheater, which is so arranged as to be entirely surrounded by a flame of the fire and is interiorly formed to compel a tortuous travel of the air current to insure 20 an efficient heating thereof prior to delivery.

A further object of the present invention is the provision of a preheater which is suspended from the stove top in a manner to avoid any interference whatever with the 25 usual use and function of the stove lids, the preheater being connected to the stove top by a single connection which in itself serves as an inlet to the preheater.

The invention in its preferred form of 30 details will be described in the following specification, reference being had particularly to the accompanying drawings, in which:—

Figure 1 is a plan illustrating the application of the invention. Fig. 2 is an enlarged 35 vertical section on line 2—2 of Fig. 1. Fig. 3 is a section on line 3—3 of Fig. 1. Fig. 4 is a perspective view of the base of the preheater.

The improved preheater comprises what I 40 term a base 1 including an approximately rectangular plate 2 having an edge wall 3 rising therefrom, said edge wall being co-extensive with the contour of the plate. The upper surface of the plate 2 within the edge 45 wall 3 is through the medium of what may be termed partition walls 4 divided to provide a central chamber 6 and the tortuous passage 7 extending from the central chamber and terminating in outlet passage 8 ex- 50 tending longitudinally of and adjacent one side of the edge wall 3. The partition walls 4 are preferably arranged as illustrated in Fig. 4, though it is to be understood that I 55 contemplate any specific arrangement of such partition walls whereby air delivered to the chamber 6 is compelled to travel the

tortuous and lengthy passage prior to reaching the outlet chamber 8. A cover plate 9 having edge flanges 10 to overlie the edge wall 3 of the base is secured upon the base 60 through the medium of bolts 11 and nuts 12, a sealing strip of asbestos 13 being interposed between the plate and upper edge of the wall 3 whereby said cover plate and base provide a preheater of hollow type having a 65 lengthy and tortuous air passage therein.

An exteriorly threaded nipple 14 is threaded into an opening in the cover in line with the chamber 6, and said nipple is passed through an opening 15 in the stove 70 top 16, nuts 17 being threaded upon the nipple on opposite sides of the stove top, and suitable packing 18 being arranged to seal the juncture between the nipple and cover. The packing is preferably of asbestos, whereby it will serve to prevent tense heat effecting comparatively small members provided primarily with a view to avoiding the sealing of the nut 17 in place by the heat and thus preventing ready disconnection of the preheater when desired. 80

The stove top 16 is in the removable portion thereof made up of the usual removable sections 19 and lids 20, and the preheater is preferably secured to one of the removable 85 sections and partly bridges the openings receiving the adjacent lids. As the preheater by reason of the length of the nipple 14 is wholly spaced from the under surface of the stove top it will be obvious that said preheater in no wise interferes with either proper heating of the lids or their removal for any ordinary or usual purpose. 90

The preheater is subjected to the direct action of the flame on top, bottom, sides and hence the air entering said preheater, is highly heated. 95

Any appropriate outlet from the chamber 8 of the preheater may be provided for the air, though in the present instance I 100 prefer to provide the edge wall 3 forming one side of said chamber 8 with comparatively small discharge openings 21 for this purpose.

What is claimed is:—

1. In a preheater for range stoves, the combination with a removable lid for the stove, of a preheater consisting of separated top and bottom walls, side walls forming with the top and bottom walls an air chamber, means for dividing the chamber into substantially serpentine passages, and a 110

central inlet tube bolted to the lid and connected to the top plate of the preheater, between the lid and upper oven wall, the central tube forming the support for the 5 preheater and whereby the heat and flames may engage all sides, top and bottom of the preheater, and one of the side walls of said preheater being provided with outlet openings.

10 2. A preheater for stoves comprising a base including a plate having an edge wall rising vertically therefrom, a cover plate secured upon such wall, the space between the base plate and the cover plate being divided by a series of longitudinal and transverse partitions to form a central chamber and a tortuous passage on each side of the central chamber, said tortuous passage including channels extending adjacent to and co-extensive with the length of the sides 20 of the edge wall, the tortuous passage on one side of the central chamber open to said

central chamber and also to the other edge channel, the edge wall adjacent one of the channels being formed with horizontally arranged openings communicating with the said channel and the upper portion of the fire box of said stove, and a hollow connector extending from the cover and detachably secured to one of the lids of said stove and for spacing said cover plate from the undersurface of the top wall of the stove and constituting the support for the preheater, said connector communicating at one end with the atmosphere adjacent the top 30 of the stove and at its remaining end with the central chamber.

In testimony whereof I affix my signature in presence of two witnesses.

WILLIAM D. FLEMING.
